UNITED STATES PATENT OFFICE

2,600,803

DENTAL EXTRACTING FORCEPS WITH
INTERCHANGEABLE BEAKS.

Thomas F. Prather, Wasco, Calif.

Application June 1, 1951, Serial No. 229,499

5 Claims. (Cl. 32—62)

1

The present invention relates to certain new and useful improvements in dental extracting forceps wherein the latter is characterized by a single pair of pliers having expressly designed force applying jaws equipped with readily applicable and removable interchangeable beaks, the jaws being novel and the beaks correspondingly novel.

As the preceding statement of the invention implies, dental surgeons have been confronted with the problem of keeping themselves equipped with innumerable forceps. There are forceps for upper and lower extractions all having peculiarly essentially shaped beaks to accommodate the task of extracting molars, bicuspids, incisors and so on and so forth. It follows that there has long existed a need for interchangeable readily applicable and removable beaks. In the circumstances, the prior art to which the invention relates reveals many and varied concepts involving the adoption and use of interchangeable beaks. Therefore, it is the purpose of the present invention to structurally, functionally and otherwise improve upon a forceps comprising a single pair of pliers with especially constructed jaws to accommodate all of the necessarily different forms of beaks required for over-all dental extraction work.

In carrying out the principles of the present invention a unique instrumentality has been evolved and produced which is possessed of the prerequisites of simplicity in construction, expediency in applying and removing the beaks, economy and in which manufacturers, repairmen and dentists will find their respective requirements and needs fully met, contained and effectually available.

More explicitly, one phase of the invention has to do with the beaks themselves, these being precision made and each characterized by a body having a suitable jaw face and having, in addition, a keying rib, a lateral retention lug on the rib, and a resilient detent also forming a part of the rib.

Then, too, novelty is predicated on the jaws on the stated pliers wherein said jaws are characterized by a groove providing a keyway, a lateral bore providing a socket for the lug, and a substantially flat blunt end on the outer or free end of the jaw providing an abutment and keeper for the coacting resilient detent, whereby to permit the beaks to be inserted and interlocked with a snap-on action.

Other objects and advantages will become more readily apparent from the following description

2 and the accompanying sheet of illustrative drawings.

In the accompanying sheet of drawings, wherein like numerals are employed to designate like parts throughout the views:

Figure 1 is a fragmentary perspective view showing the complete instrumentality embodying the especially constructed pliers and the corresponding especially constructed attachable and detachable beaks, one beak being in position and the other one removed;

Figure 2 is a side elevational view of the complete forceps ready for use;

Figure 3 is a fragmentary view in section and elevation taken approximately on the plane of line 3—3 of Figure 4, looking in the direction of the arrows; and,

Figure 4 is a cross-section on the line 4—4 of Figure 3.

- 20 In the drawings the part of the over-all instrumentality called the pliers is denoted by the numeral 6. These pliers embody conventional handle equipped levers 8 and 10 disposed in customary crossed relationship and pivotally connected together at 12. The levers, beyond the pivot, terminate in duplicate opposed pressure applying jaws 14 and 16. Each jaw is the same and a description of one will suffice for both. To this end, a flat anvil surface 18 is provided with a central longitudinal groove constituting a keyway 20. In addition, there is a right angularly disposed polygonal bore 22 which provides a lug accommodating socket. The outer or free end of the jaw is substantially flat and provides an abutment 24 which is sometimes referred to as the keeper. The readily applicable and removable beaks are denoted by the numerals 26 and 28 and here again these are duplicate mated units. In practice beaks will be paired for all required upper and lower forceps use. Basically, however, each beak is the same and comprises a rigid body portion 30 with a suitable jaw face 32, said body portion being provided on its outwardly disposed side with a longitudinal rib 34 constituting a key, said rib being provided intermediate its ends with a lateral stabilizing and retaining lug 36. The outer end of the rib is provided with a substantially V-shaped slightly resilient detent 38 which is adapted to releasably engage and bear against the keeper or abutment 24 in the manner shown. It follows that the key 34 fits into the keyway 20, the lug 36 into the socket 22 and the detent 38 engages and bears against the abutment 24. It will be evident that 50 jaws and beaks having these well chosen jointure

features are mechanically compatible and coact in providing for reliable retention of the beaks on their companion jaws. The applied mechanical principles are utilized to afford the user the assurance that the beaks will not displace themselves regardless of the firm anchorage of the tooth roots being worked upon. With this construction the dentist has at his disposal interchangeable beaks for all necessary requirements. He need only select the particular one most adapted to the case in hand to accomplish results with requisite expediency and dependability. The detents are in effect latches and aid in the snap-on and snap-off functions of the unique beaks.

Minor changes in shape, size, materials and rearrangement of parts may be resorted to in actual practice provided no departure is made from the invention as claimed.

Having described the invention, what is claimed as new is:

1. Dental forceps comprising a pair of pliers embodying crossed pivotally connected lever handles terminating at their forward working ends in duplicate jaws, said jaws having their opposed faces provided with central longitudinal grooves providing keyways and having their intermediate portions laterally bored and providing lug receiving sockets, the outer ends of said jaws being blunt and providing detent abutments, and readily attachable and detachable beaks carried by the respective jaws, each beak having a key with a lateral lug, and also having a detent.

2. Dental forceps comprising a pair of pliers embodying crossed pivotally connected lever handles terminating at their forward working ends in duplicate jaws, said jaws having their opposed faces provided with central longitudinal grooves providing keyways and having their intermediate portions laterally bored and providing lug receiving sockets, the outer ends of said jaws being blunt and providing detent abutments, and a pair of readily applicable and removable beaks, one beak carried by each jaw and each beak embodying a body portion with a longitudinal keying rib fitting in the complementary key-way, said rib having a lateral lug projecting from an intermediate portion into the cooperating lug socket, and a lateral resilient detent projecting from its outer end portion and releasably engaging the cooperating abutment.

3. Dental forceps comprising a pair of pliers embodying crossed pivotally connected lever handles terminating at their forward working ends in duplicate jaws, said jaws having their opposed faces provided with central longitudinal grooves providing keyways and having their intermediate portions laterally bored and providing lug receiving sockets, the outer ends of said jaws being blunt and providing detent abutments, and a detachable beak mounted on each jaw, each beak embodying a body portion provided on its outward side with a longitudinal keying rib keyed in the keyway of the associated jaw, a lug projecting from said rib and fitting into the adjacent socket, and a resilient detent bearing against the adjacent abutment.

4. As a new article of manufacture a quick attachable beak embodying a body having a central longitudinal keying rib of polygonal cross-section, said rib having a lateral resilient detent at its outer end and a stabilizing lug projecting laterally from its intermediate portion, said lug also being polygonal in cross-section.

5. Dental extraction forceps comprising a pair of pliers embodying crossed pivotally connected levers terminating at their forward working ends in jaws, the outer ends of said jaws being substantially flat and therefore blunt and providing detent accommodating abutments and the intermediate portions of said jaws having opposed transverse bores, the latter being at right angles to the longitudinal axes of said jaws, constituting lug accommodating sockets and being polygonal in cross-section, readily attachable and detachable snap-on beaks carried by the respective jaws, each beak having a body with a jaw face, an integral lateral lug fitting into its complementary socket, and an integral lateral detent engaging its complementary abutment.
